SYNCHRONIZING SYSTEM

Lester J. Wolf, Wilkinsburg, Pa., assignor to
Westinghouse Electric & Manufacturing Com-
pany, a corporation of Pennsylvania

Application October 6, 1930, Serial No. 486,613

2 Claims. (Cl. 172—293)

My invention relates to synchronizing systems wherein apparatus at one location in a system may be accurately controlled as to speed with respect to apparatus occupying a different position within the system. More particularly, my invention relates to synchronizing systems of the type wherein the speed of rotation of the apparatus to be synchronized is maintained in an uninterrupted state.

10 It is one object of my invention to provide an improved type of synchronizing system.

Another object of my invention is to provide a synchronizing system capable of maintaining synchronism throughout appreciable variations 15 in load on the synchronized apparatus.

Another object of my invention is to provide a synchronizing system capable of reacting quickly to changes in speed of an apparatus whereby to bring it back to synchronism without 20 appreciable time lag.

Another object of my invention is to provide a synchronizing system of merit employing thermionic devices.

Another object of my invention is to provide a 25 synchronizing system operating through the action between a plurality of frequencies.

Another object of my invention is to provide a system whereby a plurality of synchronizing forces may be controlled by a single synchronizing 30 frequency.

Another object of my invention is to provide a synchronizing system which will be sensitive and dependable in operation.

Additional objects of my invention will be 35 pointed out in the following description, taken in conjunction with the accompanying drawing, wherein

Figure 1 is a circuit diagram of a system illustrating one embodiment of my invention having means for changing over to another embodiment of my invention.

Fig. 2 is a diagram illustrating, in simplified form, a portion of the circuit disclosed in Fig. 1.

Fig. 3 is a tube-characteristic-curve diagram 45 for simplifying the explanation of the operation of the system.

Synchronizing systems, in general, are required where it is desired to maintain the speeds of two remotely located apparatus constant.

50 According to the prior art with which I am familiar, synchronizing systems may be classified broadly into two groups. One of these groups may be classified as systems of the type commonly referred to as the start-stop system, wherein the rotating apparatus at one end of a system

is caused to stop momentarily per revolution until such time as a prearranged contact on the apparatus at the other end makes contact to close a circuit which will operate to again start rotation of the first apparatus. In this manner, the speed 5 of the first apparatus is maintained in synchronism with that of the second apparatus.

Synchronizing systems of the other type embody those systems wherein the rotation of the apparatus to be synchronized is not interrupted, 10 but the apparatus is maintained in continuous rotation, and synchronism is obtained by slightly increasing or decreasing the speed of rotation in the desired direction. The accuracy and dependability of any particular system depends upon 15 the sensitivity of the elements comprising the circuits and the ruggedness of the apparatus embodied therein.

My invention relates to a synchronizing system of the second type wherein the speed of the apparatus is maintained uninterrupted. In systems of this type, a synchronizing channel is generally provided, over which a synchronizing frequency wave is continuously transmitted. This synchronizing frequency is employed to maintain 20 the apparatus at one end of the system in step with the apparatus at the other end, which apparatus is also under the control of the synchronizing frequency.

This type of system, while of general utility, 30 is very suitable for use in the field of printing telegraphs, facsimile-transmitting systems, television, etc., wherein the receiving devices must for efficient reception, be maintained in absolute synchronism with the transmitting apparatus. 35

When employed in systems of the type referred to above, it is necessary that the synchronizing system shall possess the characteristic of great sensitivity and quick action in bringing about the small changes in speed necessary to maintain 40 a synchronous condition between the receiving and the transmitting apparatus.

An obvious method of doing this is to run a synchronous motor on the synchronizing frequency, but this is often difficult because the 45 synchronizing frequency may be too high for successful operation of a synchronous motor, if much power is required of the motor.

Another method heretofore proposed is to operate the apparatus to be synchronized by a 50 motor supplied from the ordinary alternating or direct current power supply, and couple to this a smaller motor of the synchronous type which is to be operated from the synchronizing-frequency supply, the load being adjusted between 55

the two motors in such manner that a large portion of the load is taken care of by the larger motor operating from the power supply, the remainder of the load being reserved for the synchronous motor. The synchronous motor will thus function to maintain synchronism between the apparatus at the receiving end and that at the transmitting end.

My method involves an improved manner of maintaining synchronism. It is a known fact that if the winding of a squirrel-cage induction motor is supplied with a direct current, a current will be induced in the squirrel-cage rotor, and a braking action will result because of the reaction between the field produced by the direct current and that produced by the current induced in the rotor, the braking effect increasing with an increase in the direct current in the winding of the motor. This is one phenomena of which I make use in the operation of my synchronizing system and may be referred to as inductive braking.

Another phenomena which I also make use of may be referred to as thermionic braking, the operation of which will be explained in the description of the circuits.

My system is so designed that I may employ both braking effects in the operation of synchronizing, or I may so adjust the circuit as to cause the operation of my circuit to depend upon either the one or the other of the braking effects.

Referring more particularly to the drawing, I have disclosed in Fig. 1, a schematic diagram of a squirrel-cage induction motor 6 of the split-phase type, that is, the motor is designed for single-phase operation and is provided with an additional winding 3 in quadrature with the normal running winding 5 for starting purposes. When once brought up to speed, this additional winding 3 is not needed and I, accordingly, arrange to connect the winding in the plate circuit 7 of a thermionic device 9 wherein the plate current of the tube will be caused to traverse the winding and produce a braking action on the induction motor to a degree depending upon the value of the direct current in the plate circuit of the tube.

Mechanically coupled to the rotor 11 of the squirrel cage motor, I provide a frequency device 50 normally referred to as a phonic generator 13, although a device of any type may be utilized which is capable of generating frequencies of the desired value. The phonic generator comprises a rotatable member 15 of circular shape having a plurality of saw teeth 17 or substantially similar shaped projections disposed in a uniform manner about its circumference. This member is caused to rotate in proximity to a permanent magnet 19 having the shape of an arc of a circle and provided with a plurality of projecting segments 21 constituting alternate north and south poles of the magnet.

A suitable winding 23 on these poles is provided, the extremities of which are connected across the primary 25 of an audio-frequency transformer 27 through a battery 29. The movement of the saw tooth projections 17 in close proximity to the pole faces produce a periodic change in the reluctance of the magnetic circuit 60 of the magnet 19. The resultant fluctuations in the magnetic field induce in the winding 23 a current of high frequency, the particular frequency being dependent upon the number of poles and the speed of rotation of the circular element 15.

The phonic generator 13 is so designed and adjusted that the frequency generated thereby will be substantially the same as that of the frequency of the synchronizing wave which is received upon the input circuit 31 to a thermionic device 33. The potential fluctuations on the grid 35 of the thermionic device 33 as caused by the incoming synchronizing wave, will result in an amplified image of the same appearing in the plate circuit 37 of the tube, in which plate circuit is connected the primary 39 of an audio-frequency transformer 41.

The output of the phonic generator 13 and that of the thermionic device 33 are, accordingly, amplified by means of audio-frequency transformers respectively associated therewith, the secondary windings 43 and 45 of which are connected in parallel between the grid 47 and the filament 49 of the thermionic device 9 and constitute the input circuit of the tube 9.

In order to explain the thermionic braking action which I obtain as a result of the particular circuit described, I have illustrated, in Fig. 2 of the drawing, a portion of the system of Fig. 1 in simplified form.

Referring more particularly to Fig. 2, therefore, I have disclosed the audio-frequency transformers 41 and 27 constituting the output circuit of the thermionic device and the phonic generator, respectively connected in parallel across the grid 47 and filament 49. Assume, for the purpose, that the frequency, as generated locally by the phonic generator 13 coincided with that of the incoming synchronizing frequency. Under these circumstances, there will be hardly any appreciable current flowing in the secondary coils 45 and 43 of the transformers 41 and 27, respectively, since the potentials generated across the coils will be substantially equal but opposite in direction. The current passing through the secondary windings will be that due to leakage across the grid-filament path within the thermionic device 9 and this will be determined by the bias on the grid 47. Under these circumstances, the load on the phonic generator 13 will be a minimum.

Now let us assume that the frequency of the phonic generator may shift to such position as to be 180° out of phase with the synchronizing frequency, then the potentials generated across the secondaries of the transformers will be in series, 50 and a heavy current will be caused to flow through the closed low-resistance circuit defined by the two secondary windings 45 and 43.

Under this particular set of circumstances, the energy which must be produced by the phonic generator will be comparatively great and, consequently, the load on this particular element will be a maximum, thus setting up a retarding force on the induction motor 1.

By so adjusting the phonic generator with respect to normal rotation of the induction motor that the frequency of the phonic generator will be substantially 90° out of phase with that of the incoming synchronizing wave for normal operation, it will become apparent that means is thus provided whereby the phonic generator may be caused to exert a braking or a "debraking" action on the induction motor, depending on conditions existing at the moment.

The reaction between the two frequencies, as explained above in conjunction with Fig. 2, will cause the potential on the grid 47 of the thermionic device 9 to increase or decrease according to the particular phase relationship existing be-

tween the two frequencies at any particular instant.

If the device is biased in such manner as to act in the nature of a detector, the variable swing 5 of the grid 47 may be employed to vary the current in the plate circuit 7 of the thermionic device 9 in such manner as to produce a braking or "de-braking" action on the induction motor 1 at the desired moments.

10 In order to cause this braking effect to operate in such manner as to cooperate with the thermionic braking effect described above, it is necessary that the thermionic device be operated at the upper bend of its plate-current-characteristic 15 curve. At the same time, it is also desirable that the grid be biased negatively to prevent grid current from flowing in the input circuit of the tube.

This condition may be obtained through the use of a thoriated or tungsten-filament tube and 20 by impressing a high potential on the plate and a low potential on the filament. In Fig. 3, I have illustrated diagrammatically a plate-current-characteristic curve under the conditions specified, and have shown in what manner the plate 25 current of the tube 9 may be varied in the desired manner.

Assuming a zero-frequency shift to exist between the two frequencies employed in the system, then the voltage on the grid 47 because of 30 the frequency relationship will be zero and the plate current will be that represented by the negative-bias potential on the grid. The value of the plate current may, therefore, be represented by a horizontal line indicated by the reference 35 numeral 51.

Under the conditions of maximum shift between the two frequencies, a fluctuating potential will be impressed upon the grid which, under 40 these conditions, will enjoy its maximum swing. I have represented this by a sine wave curve 53 imposed on the grid bias axis 55. The particular 45 shape of the plate current produced thereby will follow a curve 57, such as that shown in the figure. It will be noted, however, that, because of the detector action of the tube, the positive half cycles of the grid potential produce smaller 50 changes in the plate current than the negative half cycles. Consequently, the average plate current may be represented by the broken line 59 which will be of a lower value than the current value representing a zero shift in frequencies.

Since I have shown it to be desirable to operate at a point intermediate the two extremities, the plate current flowing in the coil for normal 55 operation of the induction motor will be represented by the value shown by the broken line 61 in the figure.

In Fig. 3, I have not attempted to illustrate the particular wave shapes of the potentials produced by the reaction between the two frequencies but have merely employed a conventional sine wave for purpose of illustration and explanation.

When referring to the thermionic braking effect, I have shown that, when the two frequencies 60 were in synchronism, the braking action was a minimum. I have also shown that, under the same conditions, the braking action due to the current in the plate circuit of the thermionic device was also a minimum, and likewise, I have 65 shown that, when the two frequencies were 180° out of phase, the braking actions due to both the thermionic braking and the inductive braking would be a maximum.

70 Thus, it will be seen that both braking effects,

under the conditions outlined, were cooperative in their action.

If the thermionic device were operated on the lower bend of the plate-current curve, the braking action due to the one phenomena would oppose that of the other. However, it would be possible to so adjust the elements of the system that the braking effect of the one may be of much greater force than that due to the other. In which case, the system could be made to operate successfully as a synchronizing system, if 10 desired, even under those conditions.

As an alternative method of operation, the secondary 48 of the audio-frequency transformer 27 associated with the phonic generator 13 may 15 be connected in series with the secondary 45 of the audio-frequency transformer 41 associated with the thermionic device 33. To accomplish this, a switching apparatus 63 may be provided whereby the parallel connection of the two secondary coils may be broken and a series connection provided. When utilizing the series connection, the system can operate only through the use of the inductive braking effect, as no thermionic braking action will be produced in the 20 25 system as modified.

The operation of the modified system to produce the inductive braking will be substantially the same as in the previous system first described. However, the grid swing will be twice 30 as great, assuming the values of the potentials developed by the phonic generator and the synchronizing wave are of the same value, since the potentials in the series-connected circuit are added directly. This will permit of a greater 35 variation in the plate current flowing in the circuit of the thermionic tube 9 whereby substantially the same degree of synchronizing effect may be obtained as with the system wherein I employ the cooperative effect of the inductive 40 braking and the thermionic braking.

The operation of my invention may be explained as follows:

The induction motor is first brought up to synchronous speed. A convenient way of doing this 45 is to temporarily switch over the starting winding 3 to the power supply and bring the motor up to a speed where it will accelerate single phase. The starting winding may then be switched over to the plate circuit 7 of the thermionic device 9. 50 An impedance 65, comprising either a variable resistance, a variable inductance, or a variable capacity in the power-supply circuit, may be employed to bring about proximate synchronization.

If, for any reason, the load on the motor 1 55 causes the speed of the motor to change slightly to an off-synchronizing speed condition, the system will operate, in the manner described, to either increase the load or decrease the load on the motor 1 to bring it back to its synchronous 60 condition. This change in the system described by me will be a very rapid one, as the elements employed are very sensitive and quick-acting.

I have, accordingly, described a system which will fulfill the objects of my invention. Many 65 changes may be made which lie within the scope of my invention. I do not desire therefore, to be limited to the details of my invention as I have outlined them, except insofar as is necessitated by the prior art and the appended claims.

70 I claim as my invention:

1. In a synchronizing system, apparatus to be synchronized, means for generating a periodic potential of frequency proportionate to the speed of said apparatus, means for supplying another 75

- periodic potential of a frequency equivalent to the frequency of said first-named potential when the motion of said apparatus is normal, a closed circuit in which said periodic potentials are supplied in series with each other, an electric discharge device having a control electrode and a plurality of principal electrodes, means for connecting said control electrode and one of said principal electrodes to said circuit in such manner that said periodic potentials are supplied in parallel therebetween and means for coupling said principal electrodes to said generating means in such manner that said generating means is loaded in accordance with the current transmitted between said principal electrodes.
5. In a synchronizing system, apparatus to be synchronized, means for generating a periodic
- 10
- 15

potential of frequency proportionate to the speed of said apparatus, means for supplying another periodic potential, a closed circuit in which said periodic potentials are supplied in series with each other, an electric discharge device having a control electrode and a plurality of principal electrodes, means for connecting said control electrode and one of said principal electrodes to said circuit in such manner that said periodic potentials are supplied in parallel therebetween 10 and means for coupling said principal electrodes to said generating means in such manner that said generating means is loaded in accordance with the current transmitted between said principal electrodes.
